UNITED STATES PATENT OFFICE.

JOHN JOSEPH KOVACH, OF LA BELLE, PENNSYLVANIA.

STATION-INDICATOR.

1,349,160.

Specification of Letters Patent. Patented Aug. 10, 1920.

Application filed March 4, 1920. Serial No. 363,248.

To all whom it may concern:

Be it known that I, JOHN JOSEPH KOVACH, a citizen of the Republic of Czecho-Slovakia, residing at La Belle, in the county of Fayette and State of Pennsylvania, have invented certain new and useful Improvements in Station-Indicators; and I do declare the following to be a full, clear, and exact description of the invention, such as 10 will enable others skilled in the art to which it appertains to make and use the same.

This invention relates to an improved station indicator.

15 Indicators of the above mentioned character are employed for the purpose of enabling persons to determine the names of the various stations and towns before they are reached by the train, street car, or other 20 means of travel upon which the device is installed. This method of announcing the stations does away with the usual way, wherein a conductor comes through the car and announces the names of the various stations and towns being approached.

25 My device is to be placed at convenient points in the car, for instance at the end of the car so it can be readily seen by the passengers. In order to attract the attention of 30 the passengers, I have equipped the device with an audible signal, such as a bell, which will ring at the time the indicator is in operation.

I am aware that devices have been patented for accomplishing the same result that 35 I do, and I do not claim it broadly. However, these devices that I have in mind are a great deal different in construction and design from mine, and are not nearly as effective in operation as mine is. It is therefore 40 my intention and the object of this invention to generally improve upon and simplify such devices. To this end I have produced a device which is extremely simple 45 in construction, strong, durable, effective in operation and comparatively inexpensive to manufacture.

50 Other objects and advantages of the invention will be apparent during the course of the following description.

In the accompanying drawings, forming a part of this specification and in which like numerals are employed to designate like parts throughout the same;

55 Figure 1 is an end elevation of a device

constructed in accordance with my invention, the same being shown in use.

Fig. 2 is an enlarged central vertical sectional view, partly in elevation, of the device, showing the operating mechanism more 60 clearly.

Fig. 3 is a section taken on the plane of the line 3—3 of Fig. 2, looking in the direction of the arrows.

Fig. 4 is a view taken on the plane of the 65 line 4—4 of Fig. 2, the operating mechanism being shown in the position which is assumed before being moved to operative position.

Fig. 5 is a view like Fig. 4, showing the 70 position of the parts when the device is operative.

My station indicator is to be used in connection more particularly with railway cars, but it may be equally well used on street 75 cars if so desired. In the drawings, wherein for the purpose of illustration, I have shown a preferred embodiment of my invention, the numeral 1 designates the bottom or floor of a railway car, which in order to 80 support my device will be provided with an opening through which the device may be projected. The device may be connected to this floor in any suitable way and should project far enough above the upper surface 85 thereof to enable the passengers to readily see the names of the towns.

The device includes a housing 2 which forms a support for the various parts thereof and which may be made of wood if 90 desired. As before stated, a portion of this housing will project above the surface of the floor to enable the passengers to read the names of the towns. In this portion of the casing is the indicator mechanism, designated as a whole by the numeral 3. This mechanism is more clearly shown in Figs. 4, and 5, wherein there is shown pairs of rollers journaled in the support. There are two pairs of such rollers, and I have designated them as upper and lower pairs 4 and 5, respectively. The belt 6 is wound about these rollers in the manner disclosed, that is, it is wound on one of the lower rollers 4, over the upper rollers 5, and thence on the 100 remaining lower roller 4. It contains the names of the towns thereon at which the train is to stop. In order to enable the passengers to see such names, the upper portion of the support or housing will be pro- 105 110

vided with windows 7 which may be of glass or any other suitable material.

This indicator mechanism is operated by track-controlled mechanism supported in the lower portion of the support 2. This mechanism is more clearly disclosed in Fig. 2. By referring to this figure it will be seen that the numeral 8 designates a shaft which is journaled in the support or housing 2. 5 This shaft carries a pair of gears 9, and also carries, at each end, a sprocket wheel 10 with which two of the chains 11 coact, and serve to drive the indicator mechanism 3. I prefer to employ at least four chains, as 10 shown, there being two long chains, and two short chains. The long chains are connected to the sprockets 10 and to the sprockets 12 on the journals of the lower rollers 4, while the short chains are connected to the sprockets 12 and thence to sprockets 13, on the 15 journals of the upper rollers 5. It is to be noted that both of the long chains are connected to the sprockets 10 and one of them is connected to one of the sprockets 12 on 20 one of the lower rollers 4; while the other like chain is connected to the sprocket 12 on the other lower roller 4. The short chains are arranged in a similar way, that is, they are arranged to cross one another in the 25 manner shown. With this construction of driving means, I maintain a uniform and steady pull which will insure effective operation of the indicator mechanism and will prevent damaging of the belt 6 which might 30 otherwise occur owing to sudden jerking thereof if only one or two chains were employed. While I have shown and described sprockets and chains for operating the indicator mechanisms I desire it to be understood 35 that it may be accomplished with any other driving means.

Connected to the lower end of the support 2 is a vertically movable frame, indicated as a whole by the numeral 14. It includes 40 vertical arms 15, each of which is provided with an elongated slot through which the shaft 8 extends, thus permitting free vertical movement of the frame. Journaled in this frame is another shaft 16, which like 45 shaft 8 is provided with a pair of gears 17 which, as is obvious, mesh with, and impart motion to the gears 9. Rotation of shaft 16 is accomplished by a roller 18 rigidly secured on said shaft, said roller being adapted 50 to frictionally contact, a cam-shaped rail section 19 which will be disposed at a distance from the various stations and towns. This roller is held in frictional contact with the roller 19 by means of coiled springs 20 55 which are disposed between it and the lower end of the support 2. It is desired to prevent the gears 9 from rotating when the device is inoperative. To this end, I make use of a pair of bars 21 which are rigidly 60 secured at their lower ends to the shaft 16, 65

and are provided between their ends with slots 22 through which the shaft 8 extends. The upper ends of these bars extend above the gears 9 and have cross pieces 23 secured to them, the latter carrying a pair of fingers 70 24 which are designed to engage and prevent rotation of the gears 9 when the device is inoperative. However, as soon as the frame 14 is moved upwardly by reason of the engagement of the wheel 18 with one 75 of the track sections 19, the bars 21 will be caused to move upward to an extent to disengage the fingers 24 whereby the gears 9 will be permitted to rotate. If desired, a guard casing 25 may be placed over the 80 driving mechanism.

As before stated, it is my intention to employ an audible signal in order to attract the attention of the passengers when the device is in operation. This signal includes a bell 85 26 which is controlled by means of the contacts 27, which are brought into operation when the frame 14 is caused to move upwardly, as is obvious.

In use, my device will be installed at convenient points in the cars so that the passengers will be able to readily and easily see the names of the towns as they are brought to view. Within a certain or desired distance of the town, the cam-shaped rail sections 19 will be placed, in a position to be engaged by the device upon passing over the same. So, it will be seen that when the roller 18 engages one of the rail sections 19, it will be held in frictional engagement 95 100 therewith by means of the coiled springs 20. Owing to this, it will be rotated, which in turn will impart movement to the gears 17. As it approaches the center of the rail section 19 it will cause the frame 14 to move 105 upwardly against the action of the springs 20, thus bringing the gears 17 and 9 into mesh, and imparting rotation to the shaft 8 which in turn causes the sprocket chains 11 to move. It is obvious that such movement 110 of the sprocket chains 11 which are associated with the indicating mechanism 3, will cause the latter to operate. Such construction of the indicator mechanism will cause the belt device to be wound from one of the 115 rollers 4 onto the other, thus bringing the indications thereon behind the windows 7 so that the passengers in the car will be able to see them and determine the name of the station being approached.

As soon as the roller 18 has passed over the rail section 19 the parts will assume an inoperative position due to the action of the coiled springs 20. When in inoperative position the fingers 24 will engage the gears 125 9 in such a manner as to prevent rotation thereof which is undesirable and which might otherwise occur due to the jars to which the device is subjected. It is also to be mentioned that when the device is in op- 130

erative position the bell 26 will be caused to ring in the manner already set forth, thus insuring that the attention of the passengers will be directed to the name of the town 5 brought to view.

A device constructed in accordance with my invention will be found extremely advantageous, as, it will automatically indicate to the passengers, the name of the town 10 at which the train will stop next; thus obviating the usual custom now employed. The device is extremely effective in operation, and may be installed on trains now in use with extremely slight alterations of the 15 body of the cars. Consideration of the foregoing description taken in connection with the accompanying drawing will enable persons skilled in the art to which this invention relates to obtain a thorough understanding 20 of the advantages and operation of the device. Therefore, further description is deemed unnecessary.

It is to be understood that the form of my invention herein shown and described is 25 to be taken as a preferred form of the same, and that various minor changes in the shape, size, and arrangement of parts may be resorted to without departing from the spirit of the invention or the scope of the subjoined claims.

I claim as my invention:

1. A device of the class described comprising a support, movable indicator mechanism carried thereby, gearing also carried by the 35 support for imparting motion to said mechanism, a vertically movable frame, springs between the frame and the support, a shaft journaled in said frame, a roller on said shaft for frictional contact with a cam track section, and a gear on the shaft held out of mesh with said gearing by said springs.

2. A device of the class described comprising indicator mechanism, a support for the same, a shaft journaled in the support, 45 a gear on the shaft, means coacting with the gear and indicator mechanism for actuating the latter, a vertically movable frame including guide arms having slots through which said shaft extends, coiled springs between the support and frame to force the latter away from the former, a shaft journaled in the frame, a roller on the last named shaft for frictional engagement with a cam track-section, and a gear also on this shaft 55 normally held out of mesh with the first mentioned gear by said coiled springs.

3. A device of the class described comprising movable indicator mechanism, a support therefor, a gear carried by the latter 60 for imparting motion to the indicator mech-

anism, a vertically movable spring pressed frame carried by said support, a shaft journaled therein, a track-controlled-roller on the last shaft, a gear also on this shaft for mesh with the first gear, and locking means 65 for the first mentioned gear including a bar carried by the second mentioned shaft and extending above the first named gear with which it coacts, a cross-piece on this end of the bar, and a depending finger on the cross-piece for coöperation with said gear.

4. A device of the class described comprising movable indicator mechanism, a support therefor, a shaft journaled in the support, a pair of gears on the shaft, means 75 coacting with the gears and indicator mechanism for actuating the latter, a vertically movable spring pressed frame carried by the support, a shaft journaled in the frame, gears on this shaft for coöperation with the 80 first gears all of said gears being normally out of mesh, a roller fixed on the last shaft between the gears for frictional contact with a cam track-section, a pair of vertically disposed bars carried by the last named shaft, 85 each bar having an elongated slot therein through which the first shaft extends, a cross-piece secured to the upper ends of the bars, and a pair of depending fingers carried by the latter for engagement each with 90 one of the first mentioned pairs of gears.

5. A device of the class described comprising a support, upper and lower pairs of rollers journaled in the support, a belt having indications thereon, wound from one 95 of the lower rollers, across the upper pair and then on the remaining lower roller, a sprocket wheel on the journals of each of the rollers, a shaft journaled in the support, a gear on the shaft, a sprocket wheel on each 100 end of the shaft, a plurality of long and short chains coöperating with the sprocket wheels, the long chains being connected to the gears on the shaft, one of these chains being connected to the sprocket wheel on one 105 of the lower rollers while the other chain is connected to one of the sprockets on the other lower roller, the short chains being connected to the remaining sprockets on the lower rollers, directed at angles to cross each 110 other and connected to the sprockets on the upper pair of rollers, a vertically movable spring pressed frame carried by the support, a shaft journaled therein, a roller fixed on the shaft for frictional contact with a 115 cam track-section, and a gear also on this shaft for mesh with the first named gear.

In testimony whereof I have hereunto set my hand.

JOHN JOSEPH KOVACH.
